SHOCKPROOF X-RAY UNIT

Alfred Simon, Elmhurst, N. Y., assignor to Westinghouse X-Ray Company, Inc., a corporation of Delaware

Application August 9, 1934, Serial No. 739,081

5 Claims. (Cl. 250—34)

My invention relates to X-ray apparatus and particularly to what is known in the art as shock-proof units especially those operable for prolonged periods of time as in the administration 5 of therapeutical treatment for diseases and industrial radiography.

In order to construct units of this type, which are subjected to relatively high electrical potential during operation, so that the possibility of accidental shocks resulting to an operator or patient are entirely eliminated it has been the usual practice to encase the X-ray tube in a large lead lined drum rendering it ray proof. The high potential energy is supplied to the enclosed tube through suitable insulators provided in the upper portion 10 of the drum which are in turn connected to an overhead system of conductors usually extending through the wall of the treatment room to an isolated high voltage transformer. All high tension parts are thus positioned out of reach of the normal person lessening the possibility of accidental contact therewith.

However, there nevertheless exists the danger that not only a patient of abnormal height, failing 25 to appreciate the danger, might accidentally contact high voltage carrying parts but also other grounded mechanism, such as treatment tables and the like, may be moved so close to the various conductors as to cause a spark-over with resulting alarm to a patient or disaster to the mechanism. Moreover, the lead lined drums which 30 house the tube are of considerable weight thus rendering it extremely difficult to manipulate the same to the proper position for treating some 35 particular portion of the anatomy.

It has also been proposed to construct a shock-proof unit wherein the tube is encased within a grounded metallic casing with the high tension source of energy having the voltage thereof divided 40 between the electrodes of the tube and of equal potential with respect to ground. The energy is supplied to the tube through flexible grounded metallic cables with the spacing between the electrode terminals of the tube and the grounded metallic 45 casing being sufficient to prevent spark-over at operating voltages. Again, however, while the hazard of accidental shocks resulting to a patient or operator are substantially eliminated the overall size of the unit is not reduced and although, 50 by the elimination of a lead lined drum encasing the entire tube, it is reduced in weight it nevertheless remains difficult of manipulation due to its remaining weight and the size thereof.

In the utilization of such units for the administration of therapeutic treatments or industrial

radiography the tube necessarily remains energized for considerable long periods of time and, because of the high potential energy to which it is subjected, operation thereof is accompanied by the generation of considerable heat. In the prior 5 art it has been the usual practice to dissipate this heat to the surrounding atmosphere or in some instances to circulate a cooling and insulating material through the anode.

One of the primary objects of my present invention is the construction of a shockproof X-ray unit adaptable for therapeutical treatment and industrial radiography which eliminates the objectionable features inherent in prior art devices 10 of this type.

Another object of my present invention is the provision of a high tension shockproof X-ray unit 15 of compact size and weight thus increasing the facility of manipulation thereof for treating various portions of the anatomy.

Another object of my present invention is the provision of a shockproof X-ray unit in which the X-ray tube is immersed in a cooling and insulating material within a grounded metallic casing of absolute minimum size and weight, and the 25 X-ray tube is of a foreshortened length for the same applied voltages as when operating in air.

Another object of my present invention is the provision of a shockproof X-ray unit of minimum size and weight wherein the X-ray tube is immersed 30 in a cooling and insulating material within a casing and the cooling material is caused to circulate through the anode electrode of the tube and the casing for the purpose of maintaining the tube at an even temperature.

Another object of my invention is the provision 35 of a shockproof X-ray unit operable for prolonged periods of time wherein a tube of foreshortened length is immersed in a cooling and insulating material within a grounded metallic casing of 40 minimum size and weight and the tube may be readily inserted and removed from the casing thus dispensing with the necessity for a skilled mechanic.

A further object of my present invention is the 45 provision of a shockproof X-ray unit adaptable for therapeutic treatments and industrial radiography requiring operation thereof for prolonged periods of time wherein a novel circulatory system enables a cooling and insulating material to 50 flow through the anode electrode and the casing surrounding the tube.

Still further objects of my invention will become obvious to those skilled in the art by reference to the accompanying drawings wherein:

Figure 1 is an elevational view of a shock-proof X-ray unit constructed in accordance with my present invention.

Fig. 2 is an end view in elevation of the shock-proof unit shown in Fig. 1.

Fig. 3 is a sectional view in elevation and on an enlarged scale of the shockproof X-ray unit constructed in accordance with my present invention taken on the line III—III of Fig. 2.

10 Fig. 4 is a sectional view of a portion of the structure of my unit taken on the line IV—IV of Fig. 3.

Fig. 5 is a sectional view taken on the line V—V of Fig. 1, and

15 Fig. 6 is a sectional view of still another portion of my shockproof unit taken on the line VI—VI of Fig. 3.

Referring now to the drawings in detail I have shown in the several figures a shockproof X-ray 20 unit in many respects identical to that shown in the copending application of Clayton T. Ulrey, et al., Serial No. 713,462, filed March 1, 1934, wherein a shockproof unit adaptable for radiographic purposes is shown and described. The 25 device comprises a metallic casing having substantially spherical ends 5 and 6 forming compartments which are joined together by a metallic cylindrical section or passage 7 provided with an X-ray pervious window 8. The configuration 30 of the casing thus conforms substantially to the potential gradient between the enclosed X-ray tube and the casing as explained in the above noted pending application.

Each of these spherical ends 5 and 6 is provided with a reinforcing in the form of a metallic ring 9 disposed in a plane parallel with the longitudinal axis of the casing and a similar reinforcing ring 10 disposed at right angles to this axis, which are welded or otherwise rigidly 40 affixed to the respective ends.

A tubular metallic section 12 is secured to the spherical end 5 by any suitable means, such as screws 13 engaging the reinforcing ring 9, and forms an oil tight seal by the provision of a 45 gasket or the like 14. Similarly a tubular metallic section 15 extends radially from the spherical end of compartment 6 and may be secured to the reinforcing ring 9 carried thereby in the same manner as the section 12.

50 The far ends of the respective tubular sections 12 and 15 are each provided with a sleeve 16, welded or otherwise affixed thereto, which has a portion thereof of increased diameter threaded internally and externally and forming a pair of 55 annular shoulders or the like 17 and 18. An insulating bushing 19 extends inwardly of the tubular metallic section 12 and has a portion thereof of slightly increased diameter which is adapted to be held in firm engagement with the shoulder 17, by means of an annular threaded ring 20, engaging the internally threaded portion of the sleeve 16. This ring 20 is screwed in place by a suitable tool inserted in recesses 22 provided therein and in order to form an oil tight joint a suitable gasket or packing 23 may be interposed between the bushing 19 and the ring 20 which rests upon the shoulder 18.

70 The lower end of the insulating bushing 19 is provided with a threaded portion of slightly reduced diameter to which is secured an insulating cap 24 forming an end closure for the bushing 19 with a suitable gasket 25 being provided to assure an oil tight joint. A pair of recessed metallic sleeves 26 and 27 are provided in the cap 24, as 75 can be more readily seen from Fig. 4, each of

which has a stud portion 28 protruding below the surface of this cap. Secured to the stud portion 28 of the sleeves 26 and 27 are a pair of cast or pressed metallic terminals 29 and 30 having a substantially rounded contour and free from sharp points and edges. 5

Each of these terminals is provided with an elongated slot 32 of sufficient width to allow free turning of a locknut 33 for securing the terminals to the stud portion of the sleeves. A further pair of recesses 34 and 35 are provided in the terminals 29 and 30 which are disposed at right angles to the longitudinal axis of the terminals. 10

The tubular section 15 is likewise provided with an insulating bushing 36 similar to the bushing 19 also provided with a cap 37 forming an enclosure having a recessed sleeve provided with a stud portion 38 identical with the portion 28 of the sleeves 26 and 27. An angular metallic strip 39 is secured to this stud portion 38 by means of a locknut 40 and a set screw 42 is provided in this strip 39 forming a terminal. 15

A cylindrical shaped X-ray tube 43 provided with an anode 44 and a cathode 45 is concentrically disposed within the casing relative to the longitudinal axis thereof and has its cathode end supported by the terminals 29 and 30 through a 20 slide engagement with the recesses 34 and 35 provided therein. 25

The anode terminal of the X-ray tube comprises a hollow metallic member 46 having a substantially rounded contour free from all points and edges. This is secured to the hollow anode stem and is electrically connected to the set screw 30 terminal 42 through the intermediary of a flexible conductor 47 with the anode end of the tube being supported in a manner to be hereinafter more fully described. The terminals 29 and 30 thus constitute the cathode terminal for the 40 X-ray tube, which like the anode terminal 46, all have a substantial radii of curvature and are disposed in spherical relation with reference to the spherical ends 5 and 6, respectively, for the purpose of reducing the electrostatic field concentration thereabout and preventing the formation of corona and sparkover to the casing. 45

The X-ray tube 43 is thus disposed in spaced relation to all metallic parts of the casing with the envelope substantially concentric with the cylindrical passage 7 and the ends thereof with their respective terminals extending into the compartments formed by the spherical ends 5 and 6 and coaxially disposed relative to the latter. The respective recessed sleeves 26 and 27 being of 55 metal are thus electrically connected to the cathode of the X-ray tube and similarly the recessed sleeve carried by the cap 37 is electrically connected to the anode of the tube. 55

In order to energize the X-ray tube a pair of 60 high tension cables 48 and 49, having a metallic sheathing 50, are provided which extend from a suitable high tension source of electrical energy (not shown) and are connected to the metallic casing housing the X-ray tube. 65

The respective cables have the metallic sheathing 50 removed therefrom for a short distance of their length and these portions are surrounded by insulating sleeves, as shown at 52. These insulating sleeves are concentrically disposed relative to the respective insulating bushings 19 and 36 and extend longitudinally thereof through the annular ring 20 being provided near their upper extremities with a portion of slightly reduced diameter forming a shoulder 53. 70 75

Contact terminals 54 and 55 (Fig. 4) are carried by an insulating member forming the end closure for the sleeve 52 and are connected to the conductors of the cables 48 which supply the cathode heating current as well as one side of the high potential energy. These terminals protrude beyond the exterior surface of the insulating sleeve 52 a short distance to form studs which engage the recessed metallic sleeves 26 and 27 10 in turn electrically connected to the cathode of the X-ray tube. In a similar manner the insulating sleeve surrounding the unsheathed portion of the cable 49 is provided with a projecting stud connected to the electrical conductor of this cable 15 which likewise engages the recessed sleeve carried by the cap 37 in turn connected to the anode of the X-ray tube.

The details of construction of the connection of the respective metallic sheathed cables 48 and 50 to the metallic casing are identical so that a description of the connection of cable 48 should be sufficient. A clamp 56 formed of two semi-cylindrical sections secured together by suitable means, such as screws 57, is adapted to firmly engage the metal sheathing 50 of the cable 48 and the upper extremity of the insulating sleeve 52. This clamp flares slightly outwardly and is then bent inwardly to form a groove for retaining a metallic ring 58 against the shoulder 53 formed by the reduced diameter portion of the insulating sleeve 52.

An annular collar 59 fits around the lower part of the clamp 56 which threadedly engages the externally threaded portion of the ring 20 thus forcing the ring 58 against the shoulder 53 and the insulating sleeve 52 inwardly of the tubular section 12 so that the contact terminals 54 and 55 are maintained in slidable engagement with the recessed sleeves 26 and 27.

In order to reduce the insulation requirements between the high voltage terminals of the X-ray tube and the grounded metallic casing it is customary to ground the midpoint of the transformer serving as the high voltage source thus necessitating insulation requirements between the terminals of the tube and the metallic casing equal to one-half that of the high potential source to ground. Moreover, to still further reduce the insulation requirements below that normally required at the same applied voltage for the tube when operating in air, the metallic casing is filled with an insulating and cooling material, such as oil 60, completely immersing the X-ray tube 43 and surrounding the insulating bushings 19 and 36 thus augmenting the insulating characteristics between the unsheathed portions of the cables 48 and 49 and the metallic sections 12 and 15 of the casing. The connection of the insulating bushings 19 and 36 to the casing as well as the high tension cables 48 and 49 accordingly forms an oil tight seal enabling the casing to be moved to any desired position without leakage.

During operation of the tube for prolonged periods of time, such as in the administration of therapeutical treatments and industrial radiography, considerable heat is generated which is dissipated to the cooling and insulating material causing an expansion thereof and necessitating the provision of some compensating means.

However, in my present structure I eliminate the necessity for the provision of expansion compensating means by maintaining the operation of the tube at a much lower temperature and enabling a circulation of the cooling and insulating

means through the hollow anode stem of the X-ray tube and the casing.

To this end the anode of the X-ray tube may be constructed in the manner shown and claimed in the copending application of D. Gordon Sharp, Serial No. 735,181, filed July 14th, 1934, wherein an inlet conduit 62 is provided for the ingress of the oil 60 and after circulating through the anode in the vicinity of greatest heat it discharges through the hollow anode stem, which forms 10 an outlet conduit 63 concentrically disposed relative to the inlet conduit, into the casing as shown by the arrows in Fig. 3. Before insertion of the tube in the casing the inlet conduit 62 is screwed into the hollow anode stem and a disc of insulation material 64 is then screwed into the inlet conduit 62 and fastened in place by suitable means, such as a locknut 65.

The insulated disc 64 is provided with a longitudinal passage 66 which communicates with the 20 inlet conduit 62 and a suitable bushing 67 threadedly engages the disc 64 in alignment with the passage 66 for connection to an intake line from a reservoir or the like, housing the cooling and insulating material. The flexible conductor 47 is 25 first connected to the strip 39 by the set screw 42 and the X-ray tube slid into the casing with the cathode terminals slidably engaging the recesses 34 and 35. The insulating disc 64 is then secured 30 to the reinforcing ring 10 carried by the casing in an oil tight manner by the provision of suitable fastening means, such as screws 68 and gasket 69 and when in place cooperates with the inlet conduit 62 in forming a support for the 35 anode end of the tube 43.

The opposite end or compartment 5 is likewise provided with an insulating disc 70 secured thereto by suitable means, such as screws 72 and a gasket 73 is provided for rendering the connection oil tight in the same manner as the disc 40 64. A passage 74 communicates with the interior of the casing and a bushing 75, which is adapted to be connected to the return line leading to the oil reservoir, threadedly engages this disc 70 and, like the bushing 67, has a male portion 45 engageable with a female portion surrounding the return line to form an oil tight connection.

In order to make the entire unit X-ray proof except at the ray pervious window 8 a layer of 50 metal 76 of high atomic weight, such as lead, covers the entire casing forming an integral part thereof except at the connection of the discs 64 and 70. However, end caps 77 formed of the same material as the layer 76 are detachably connected to the insulating discs by suitable fastening means, such as screws 78 to enable detachment thereof and of the discs 64 and 70 for insertion and removal of the X-ray tube 43.

The cylindrical passage portion 7 of the casing 60 may be provided with reinforced portions 79 and 80, as seen more clearly in Figs. 3 and 5, to which suitable handles (not shown) may be secured for moving the entire unit to various angular positions in its support to align the pervious window 65 with the particular portion of a patient it is desired to treat. Moreover, this window 8 is not only pervious to X-rays but also to visible light in order that an operator may readily determine when the cathode electrode 45 is incandescent.

During operation of the tube the cooling and insulating material 60 flows from the reservoir through the inlet line, the passage 66 in the disc 64, and inlet conduit 62 to the anode where it contacts the portions thereof of greatest heat.

The material then flows outwardly through the hollow anode stem 63 into the casing, as shown by the arrows, and after circulating about the tube and interior of the casing, returns to the reservoir through the passage 74 in the disc 70. This circulation of the oil in the casing after its passage through the anode serves not only to pre-cool the same to a slight extent prior to its return to the reservoir, but the efficiency of heat transfer is considerably increased, due to circulation of the oil about the tube and casing, where convection currents dissipate some of the heat through the walls of the casing to the surrounding atmosphere. Furthermore, the cooling and insulating material within the casing being in circulatory relationship with the anode cooling system enabling the same to flow into the reservoir thus dispenses with the necessity for the provision of expansion bellows or other compensating means for increases in volume of the material upon a rise in temperature.

It thus becomes obvious to those skilled in the art that I have provided a shockproof X-ray unit of minimum size and weight thus increasing the facility of manipulation thereof in the administration of therapeutical treatments and industrial radiography. The X-ray tube is made of foreshortened length for the same applied voltage as when operating in air, due to the utilization of a cooling and insulating material of high dielectric strength, and the casing has a contour conforming to the electrical field distribution or potential gradient from the tube to the surrounding casing thus enabling a minimum spacing thereof determinable by the dielectric strength of the insulating material.

This accordingly permits not only the casing to be of minimum size and weight but the entire volume of insulating and cooling material required within the casing is considerably reduced which still further reduces the weight of the unit. Moreover, a circulatory system of high efficiency is provided for cooling of the tube during operation for prolonged periods of time by causing the cooling and insulating material to circulate from a reservoir in series relationship through the anode of the tube and then through the casing prior to its return to the reservoir for final cooling.

Although I have shown one specific embodiment of my invention I do not desire to be limited thereto as various other modifications of the same may be made without departing from the spirit and scope of the appended claims.

What is claimed:

1. A shockproof X-ray unit comprising a grounded metallic X-ray opaque casing having substantially spherical ends connected by a tubular passage, an X-ray tube concentrically disposed within said casing having a cathode and an anode which becomes heated during operation, a body of cooling and insulating material in said casing and immersing said X-ray tube, an inlet duct forming a support for the anode end of said tube and having a passage extending from the anode of said tube and communicating with a reservoir for the ingress of the cooling and insulating material, an outlet duct formed in said anode and extending therefrom to said casing for discharging said material into said casing to immerse said X-ray tube after circulation of said material through said anode, and a closure member for one end of said casing provided with a passage communicating with said casing and the reservoir to complete a circulatory

system for the purpose of cooling said tube during operation.

2. A shockproof X-ray unit comprising a grounded metallic X-ray opaque casing provided with an X-ray and light pervious window and having substantially spherical ends connected by a tubular passage, an X-ray tube concentrically disposed within said casing provided with a cathode and an anode which becomes heated during operation and having electrode terminals of substantial radii of curvature spherically disposed with reference to the spherical ends of said casing to reduce the electrostatic field concentration therebetween, a body of cooling and insulating material in said casing and immersing said X-ray tube, means connected to the anode of said X-ray tube and to said casing for causing said cooling and insulating material to flow through said anode and said casing in circulatory relationship to cool said tube during operation, flexible grounded metallic cables adapted to supply high tension electrical energy to said tube for causing energization thereof, and means for connecting said cables to said casing and to the electrode terminals of said tube to form an oil tight seal therebetween.

3. A shockproof X-ray unit comprising a grounded metallic X-ray opaque casing provided with an X-ray and light pervious window and having substantially spherical ends connected by a tubular passage, an X-ray tube concentrically disposed within said casing provided with a cathode and an anode which becomes heated during operation and having electrode terminals of substantial radii of curvature spherically disposed with reference to the spherical ends of said casing to reduce the electrostatic field concentration therebetween, a body of cooling and insulating material in said casing and immersing said X-ray tube, an inlet duct forming a support for the anode end of said tube and having a passage extending from the anode of said tube and communicating with a reservoir for the ingress of the cooling and insulating material, an outlet duct formed in said anode and extending therefrom to said casing for discharging said material into said casing to immerse said X-ray tube after circulation of said material through said anode, a closure member for one end of said casing provided with a passage communicating with said casing and the reservoir to complete a circulatory system for the purpose of cooling said tube during operation, flexible grounded metallic cables adapted to supply high potential electrical energy to said tube for causing energization thereof, and means for connecting said cables to said casing and to the electrode terminals of said tube and forming an oil tight seal therebetween.

4. A shockproof X-ray unit comprising a grounded metallic X-ray opaque casing having substantially spherical ends connected by a tubular passage, an X-ray tube concentrically disposed within said casing having a cathode and an anode which becomes heated during operation, a body of cooling and insulating material in said casing and immersing said X-ray tube, detachable closure means at each end of said casing forming an oil tight seal therewith, one of said closure means being connected to said anode and forming a support for the anode end of said tube and provided with a passage communicating with the anode and a reservoir to enable the ingress of the cooling and insulating material, and the remaining closure means being also provided with a passage communicating with said

casing and the reservoir to enable the egress of said cooling and insulating material after circulation thereof through the anode of said tube and said casing.

5. A shockproof X-ray unit comprising a grounded metallic X-ray opaque casing having substantially spherical ends connected by a tubular passage, an X-ray tube concentrically disposed within said casing having a cathode and an 10 anode which becomes heated during operation, a body of cooling and insulating material in said casing and immersing said X-ray tube, a detachable closure means secured to said casing and forming an oil tight seal therewith for the

purpose of enabling the insertion and removal of said tube comprising a disc of insulating material provided with a passage therein having one end thereof communicating with a reservoir, an inlet duct connected to the anode of said X-ray tube and to said disc for supporting one end of said tube, and communicating with the passage provided in said disc to enable the ingress of oil to said anode, and means forming a discharge return path to the reservoir for the egress of 10 said cooling and insulating material including the interior of said casing. 5

ALFRED SIMON.
